UNITED STATES PATENT OFFICE.

NATHAN STEDMAN, OF AURORA, INDIANA.

COTTON-PRESS.

SPECIFICATION forming part of Letters Patent No. 235,390, dated December 14, 1880.

Application filed October 21, 1880. (No model.)

To all whom it may concern:

Be it known that I, NATHAN STEDMAN, of Aurora, in the county of Dearborn and State of Indiana, have invented certain new and useful Improvements in Cotton-Presses, of which the following is a specification.

My invention is an improvement upon that class of presses for baling cotton, hay, and similar substances which employs a screw and nut to operate a reciprocating follower or platen within a box, the cotton or other substance being thrown loosely into the box at the top, the top closed and battened, and the platen forced upward to reduce the mass to a bale of the required size.

This invention consists in a novel construction and combination of parts for producing an efficient press, which will be fully herein-after described and claimed. The improvements are clearly shown in the accompanying drawings, illustrating my invention, in which—

Figure 1 represents the front elevation of a cotton-press containing my improvement. Fig. 2 is a side elevation thereof. Fig. 3 is a plan of the base-frame and driving-gear. Fig. 4 is a detached elevation of the master bevel-wheel, driving-pinion, and pulleys. Fig. 5 is an elevation of the friction-pulleys and driving-pulley. Fig. 6 is a detached view of the clutch, actuating-pulley, and bevel-pinion; and Fig. 7 is a detached view of the top of the cotton-box.

Similar letters of reference indicate similar parts.

A is the base-frame, consisting of two long longitudinal timbers, $a a$, and two shorter parallel timbers, $a' a'$, united by cross-timbers a^2 a^2 . B is an upright box, secured to the base-frame A by tie-bolts $b b$. C is the platen; D, the pressure-screw; E, the master bevel-wheel; F F' , the actuating-pulleys; G G' , the bevel-pinnions; H, the stand supporting the master bevel-wheel E; $h h$, the inner, and $h' h'$ the outer, bearings of the actuating-shafts $f f'$. I is the friction-wheel which elevates the platen C, and J is the friction-wheel which depresses the platen, made larger in diameter than the wheel I, to produce a quick return.

K is the driving-wheel, receiving the power from the belt L. M is a cast-iron stand or

plate, bolted to the timbers $a a$ of the frame A in such a manner that it may be adjusted laterally to vary the separation of the friction-wheels I and J and the pulleys F' and F, respectively. $m' m'$ are tempering-screws for adjusting the stand M in position upon the base A. N is the swivel-head, pivoted to the stand or plate M at n , and provided with bearings $n' n'$, for the reception of the driving-shaft O. P is a hand-lever mounted upon one of the timbers a of the frame A, and connected to the swivel-head N by means of the link p.

The pressure of the hand-lever toward the press engages the friction-wheel I and pulley F' and elevates the platen C, and the pressure of the hand-lever P in an opposite direction engages the friction-wheel J and pulley F and produces a converse motion of the bevel-wheel E and platen C.

Upon the hubs of each of the pulleys F and F' are cast heavy clutches f^2 , Fig. 6, with two or more equidistant jaws, which match corresponding jaws in the hubs of the bevel-pinnions G and G', the clutch on the pulley F or F' being united to the corresponding clutch on the pinions G or G' by means of bolts g , as shown in Fig. 6.

The friction-wheels I and J may be of any suitable material.

B' B', Figs. 1, 2, and 7, are the two parts or doors of the press-head, against which the cotton is upwardly pressed by the platen C. The two doors or parts of the press-head are hinged at their outer ends to the compressing-box B, and close inwardly and centrally, as shown by dotted arcs in Fig. 7.

B² B² are heavy stirrups passed around the longitudinal timbers of the top frame of the box, and projected upwardly far enough to clear the battens $b' b'$ on the doors of the press-head and receive the wedges B³ B³. Upon removing the wedges B³ B³ the two hinged parts or doors of the press-head B' B' are turned back on their hinges, as shown in Fig. 7, thereby exposing the entire area of the box B for the reception of loose cotton.

The box being opened and the platen C run down, cotton is filled in until the two hinged parts B' B' of the press-head will just close under pressure from without, when the platen

C is then forced up and the bale formed in the usual manner.

The bevel-wheel E has a hub, e', or internally-threaded sleeve, which engages the screw 5 D, and this recess or hub may be made with or in a separate piece from the said wheel.

I am aware that the use of a screw and nut driven by a sweep worked by man or horse power for the operation of a platen in the 10 pressing-box of a hay or cotton press is not new, and that the pulleys F F' and friction-wheels I and J have been used before to produce an alternating motion; but these I do not claim, broadly.

15 Having described my invention, what I claim is—

1. The combination of the bevel-wheel E, having an internally-threaded sleeve formed in it or secured to it, screw D, bevel-pinions G 20 G', pulleys F F', shaft O, and stand H with

the platen C and box B of a cotton-press, substantially as and for the purpose described.

2. The combination of the friction-wheels I and J, shaft O, swivel-head N, and adjustable table M with the base-frame A of a cotton-press, 25 substantially as and for the purpose described.

3. The combination, with the bevel-wheel E in a baling-press, of the pulley-wheels F F', each provided with a clutch, the pinions G G', adapted to engage the bevel-wheel, the 30 shaft O, and the friction-wheels I J, substantially as described.

In testimony whereof I have signed my name to the foregoing specification in the presence of two subscribing witnesses.

NATHAN STEDMAN.
